UNITED STATES PATENT OFFICE.

LOUIS HOFMANN, OF NEW YORK, N. Y., ASSIGNOR OF PART TO GEORGE E. FOERSTER, OF NEW YORK, N. Y.

NON-REFILLABLE BOTTLE.

SPECIFICATION forming part of Letters Patent No. 759,178, dated May 3, 1904.

Application filed December 3, 1903. Serial No. 183,635. (No model.)

To all whom it may concern:

Be it known that I, LOUIS HOFMANN, a citizen of the United States, residing in Brooklyn borough, city of New York, in the county of Kings and State of New York, have invented certain new and useful Improvements in Non-Refillable Bottles, of which the following is a specification.

This invention relates to means for preventing the refilling of bottles; and its object is to provide an article acceptable to the trade which can be made at low cost, is not liable to get out of order, and is effective to prevent refilling of the bottle.

15 In the accompanying drawings, Figure 1 is a sectional view of a bottle provided with my improvements, the lower portion of the bottle being broken away. Fig. 2 is a perspective view of a valve and a flanged plug to which the valve is hinged. Fig. 3 is a view of an upper baffle-plate. Fig. 4 is a view of a lower baffle-plate. Fig. 5 is a perspective view of a cone.

20 In the several views like signs denote like parts.

The bottle (designated as 1) is usually made of glass and is provided with a plain neck 2. Fitting over said neck and preferably cemented thereto, as at 3, is a glass tube 4, which projects considerably above said neck. Resting upon the rim of said neck is a cap 5, preferably of glass, and confined between the rim of said neck 2 and a shoulder 6, formed within said glass tube 4. Said cap or plate 5 is provided with a central perforation or outlet 7, in which is fitted a hollow plug 8, of cork or hard rubber, (preferably the latter,) said plug having a flange 9, which rests upon said cap 5. To ear 10, projecting upwardly from said flange, is pivoted, by means of ears 11, a lid or valve 12, which closes normally the perforation 13 in said plug. A hard-rubber or other hollow cone 14 fits tightly at its base portion within the glass tube and rests upon the cap 5. The cone is provided with a perforation or perforations 15 at points near its base. A ball 16, preferably of glass, is confined within the cone and rests upon the valve 12, closing the same. A baffle-plate 17, preferably a

disk of glass, is confined between the top of 50 said cone and a second shoulder 18, formed within the glass tube 4 above the first shoulder 6. A co-operative glass baffle-plate 19 fits up against a third shoulder 20, formed within the tube above shoulder 18. The plate 55 17 is provided at intervals with openings 21 in its edge, and the plate 19 is provided with like openings 22, which are out of line or alternating with the openings 21 to prevent access by means of a wire to the interior of 60 the glass tube 4. The latter is prolonged above said shoulder 18 to receive a stopper 23.

Normally the valve is held down by the ball, so that it is impossible to introduce liquid into the bottle past the valve. When the 65 bottle is inverted, if it is attempted to introduce liquid the upward movement of the liquid closes the valve. Moreover, the valve may be of a quality of hard rubber which is lighter than water or of cork, so that it will 70 float under such conditions, and it is not essential in all cases that the valve be hinged. When the bottle is lying on its side, the ball, which nearly fills the cone, rolls down the side of the latter and rests against the valve, 75 thus holding the same closed.

Having thus described my invention, I claim—

1. The combination with a bottle having an integral neck, of a glass tube inclosing and 80 closely fitting said neck and cemented thereto, a glass cap having a central perforation and confined between the rim of said neck and a shoulder formed within said tube, a hard-rubber hollow plug fitting in said perforation and 85 provided with a flange which rests upon said glass cap, a hard-rubber valve hinged upon said flange, a hard-rubber hollow cone whose base fits in said glass tube and rests upon said glass cap, said cone being provided with perforations, a glass ball confined within said cone and resting upon said valve, a glass baffle-plate confined between the top of said cone and a second shoulder formed within said 90 glass tube above the first shoulder, and a co-operative glass baffle-plate fitting within said tube above said second shoulder and seated against a third shoulder formed above the sec- 95

ond; said glass tube being prolonged above said third shoulder to receive a stopper.

2. The combination with a bottle having an integral neck, of a tube inclosing and closely fitting said neck, a cap having a perforation and confined between the rim of said neck and a shoulder formed within said tube, a valve upon said cap, a perforated hollow cone in said tube covering said valve, a ball confined 5 within the cone and resting upon the valve, and baffling means above said cone.

3. The combination with a bottle having an integral neck, of a tube inclosing and closely fitting said neck, a cap having a perforation and confined between the rim of said neck and a shoulder provided within said tube, a valve upon said cap, a perforated hollow cone fitting 15 in said tube and covering said valve, a ball confined within the cone and resting upon the valve, a baffle-plate confined within said tube 20 between the top of said cone and a second shoulder provided in said tube, and a second baffle-plate supported in said tube above the first and below the mouth of the tube.

25 4. The combination of a glass bottle having an integral neck, a glass tube inclosing and closely fitting said neck and cemented thereto, a glass cap having a central perforation and confined between the rim of said neck and a shoulder provided within said tube, a valve upon said cap, a hollow cone whose base fits in said glass tube and rests upon said glass cap, said cone being provided with perforations, a ball confined within said cone and resting upon 30 said valve, and baffling means.

5. The combination of a glass bottle having an integral neck, a glass tube inclosing and closely fitting said neck and secured thereto, a cap having a perforation and confined upon the rim of said neck, a valve upon said cap, a hollow cone whose base fits in said glass tube, 40 said cone having a perforation, a ball confined within said cone for closing said valve, and baffling means.

6. The combination with a bottle having an integral neck, of a tube inclosing and closely fitting said neck, a cap upon said neck, said cap being provided with a perforation, a buoyant valve upon said cap and closing the perforation in the latter, a hollow cone above 45 said valve, and a ball within said hollow cone 50 for closing said valve.

7. The combination of a glass bottle having an integral neck, a glass tube confining and fitting closely upon said neck and cemented thereto and provided with three interior shoulders or annular seats, a cap having a perforation and held upon the rim of said neck by means of one of said shoulders, a valve for 55 said cap, a hollow cone resting upon said cap, a ball within said cone and resting upon said valve, a baffle-plate confined between and by 60 said cone and the second of said shoulders, and a second baffle-plate seated against the third of said shoulders.

LOUIS HOFMANN.
